Inventor
John J. Brabant
By his Attorney
W. T. Riswell

UNITED STATES PATENT OFFICE.

JOHN J. BRABANT, OF SMITHSTOWN BRANCH, NEW YORK.

MUFFLER.

Application filed November 10, 1919. Serial No. 336,848.

To all whom it may concern:

Be it known that I, JOHN J. BRABANT, a citizen of the United States, and a resident of Smithtown Branch, in the county of 5 Suffolk and State of New York, have invented a certain new and useful Improvement in a Muffler, of which the following is a full, clear, and exact specification.

This invention relates more particularly 10 to a class of devices adapted to be used in conjunction with combustion engines.

My invention has for its object primarily to provide a muffler designed to be employed for silencing the sound produced by the force 15 of the discharges of combusted gaseous products exhausted from internal combustion engines by causing the course of travel and velocity of the products from the engines to be checked and diverted in a manner 20 whereby an effectual reduction of the pressure and elimination of sound at their final liberation from the exhaust outlets will be obtained. This is accomplished essentially by providing a main chamber having 25 an inlet adapted to be connected to the exhaust of an internal combustion engine as well as having an outlet for discharging the combusted gaseous products after passage through the chamber. Within the main 30 chamber are spaced perforated chambers or baffles provided so that the stream of the products will be dissipated and diverted from a direct course through the main chamber, while on the main chamber are intake 35 ports whereby air will be forced into the main chamber for admixture with the gaseous products by their suctional action during the flow through the main chamber, and in turn the sound resulting from the pressure. 40

A further object of the invention is to provide a muffler of a simple, efficient and durable construction which may be made in any suitable shape and size.

With these and other objects in view the invention will be hereinafter more fully described with reference to the accompanying 50 drawing forming a part of this specification in which similar characters of reference indicate corresponding parts in all the views, and will then be pointed out in the claim at the end of the description.

In the drawing, Figure 1 is a fragmentary

view showing in perspective one form of muffler embodying my invention, and

Fig. 2 is a fragmentary view showing a section taken on the line 2—2 of Fig. 1.

The device or muffler has a main chamber 60 or shell 10 which may be of any suitable shape and size, though the chamber is preferably of a form having a tapered cylindrical side wall 11 with a head plate 12 in its larger end, and protruding from an opening 65 in this plate is an inlet pipe 13 adapted to be connected to the exhaust port or pipe of an internal combustion engine, not shown, so that the combusted gaseous products from the engine will pass through the pipe into 70 the main chamber 10. In the second end of the chamber 10 is a perforated outlet plate or baffle 14, and this outlet end of the chamber may be connected to the delivery pipe, as 15, through which the exhausted products of combustion from the main chamber 75 are finally discharged.

Interiorly of the main chamber or shell 10 between the inlet 13 and the outlet 14 are spaced perforated chambers or baffles, as 80 16, 17, 18, which serve to dissipate and divert the course of the stream of combusted gaseous products when flowing through the main chamber from its inlet to its outlet. The baffle chambers 17 and 18 are preferably 85 of similar formations, each being composed of a substantially cone-shaped wall 19 with an opening 19^a in its apex, while in the second end of the wall 19 of each of the chambers is a plate 20. In the plate 20 of each 90 of the chambers are spaced perforations 21. The baffle chamber 16 also has an approximately cone-shaped wall 22 with an opening in its apex from which protrudes a nib or tube 23 disposed toward the outlet 14 of the 95 main chamber 10, while in the other end of the baffle chamber 16 is a plate 24. In the plate 24 of the baffle chamber 16 are spaced 100 perforations 25. The baffle chambers 16, 17, 18 are arranged in the main chamber 10 so that their perforated plates 20 and 24 respectively are disposed across the passage through the chamber, and these baffle chambers are soldered or otherwise secured to the side wall 11 of the chamber. The openings 105 19^a as well as the passage of the tube 23 of these baffle chambers are thereby disposed toward the perforated outlet or baffle 14 of the main chamber. When the gaseous products of combustion are exhausted from the 110

engine they will be admitted in the main chamber 10 through the inlet pipe 13, and the products will pass through the perforations of the plate 20 into the interior of the chamber 18, thence through the opening 19^a of the baffle chamber. The flow of the products of combustion will then be through the perforations of the plate 20 of the baffle chamber 17 into the interior of this chamber and through the opening 19^a of the wall 19 of the baffle chamber. From the baffle chamber 17 the products of combustion will pass through the perforations of the plate 20 of the baffle chamber 16, thence into the interior of the chamber and through the tube 23 of the chamber for being exhausted through the perforated outlet plate or baffle 14 of the main chamber into the final distribution pipe 15. The stream of the gaseous products passing through the main chamber will thereby be diverted from a direct course as well as being dissipated for causing a reduction of the sound producing pressure of the products, and during the travel of the gaseous products the tendency of causing back pressure is overcome by the provision of air intake ports, as 26, 27, 28.

The intake ports are preferably of like formations, and each intake consists of a band 29 of approximately a cone-shape or funnel shape. The bands are arranged at spaced intervals on the exterior of the main chamber so that their reduced or apiced end parts surround the baffle chambers 16, 17, 18 and so that their flared open ends are disposed toward the inlet pipe 13 of the main chamber. The apiced ends of the bands 29 are soldered or otherwise fixed to the side wall 11 of the main chamber 10, and the parts of the side wall of the main chamber corresponding to the interior of the cone-shaped bands are perforated, as at 30. During the travel of the products of combustion through the main chamber, as above explained, a suctional action will occur, and in

turn air will be drawn in the cone-shaped bands 29 as well as through the perforations 30 of the side wall of the main chamber. The currents of air will then mix with the dissipated products of combustion for further reducing the pressure of the products and silencing their sound producing force at their final liberation from the outlet pipe 15 of the main chamber.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:—

In a muffler, the combination with a chamber having a tapered cylindrical wall perforated intermediate its ends and having in one of its ends an inlet as well as having in its other end a wall with outlet perforations, of spaced substantially funnel shaped members encircling the exterior of the perforated portion of the wall of the cylindrical chamber, and substantially cone-shaped chambers arranged in spaced relation across the interior of the perforated portion of the cylindrical chamber, said cone-shaped chambers having outlets in their apices disposed toward the outlet perforations of the end wall of the cylindrical chamber and having perforations in the walls of their bases.

This specification signed and witnessed this 8th day of November A. D. 1919.

JOHN J. BRABANT.
